UNITED STATES PATENT OFFICE.

WILLIAM H. SMYTH, OF BERKELEY, ASSIGNOR TO THE KING MORSE CANNING COMPANY, OF SAN FRANCISCO, CALIFORNIA.

CAN-TESTING MACHINE.

SPECIFICATION forming part of Letters Patent No. 394,664, dated December 18, 1888.

Application filed June 16, 1888. Serial No. 277,364. (No model.)

To all whom it may concern:

Be it known that I, WILLIAM H. SMYTH, of Berkeley, Alameda county, State of California, have invented an Improvement in Can-Testers; and I hereby declare the following to be a full, clear, and exact description of the same.

My invention relates to a machine for determining whether the seams of the cans have 10 been properly soldered before they have been filled.

It consists of an inclined rotary table or carrier, into which the cans are placed, one side of this carrier passing beneath the surface of water in a containing-tank, so that as 15 the cans are carried beneath the water escaping bubbles will indicate the leaky ones.

It consists, also, of a mechanism for discharging and drying cans, a mechanism by 20 which the defective cans may be separated from the good ones and discharged into another chute, and in certain details of construction, all of which will be more fully explained by reference to the accompanying 25 drawings, in which—

Figure 1 is a vertical central section of my machine. Fig. 2 is a plan view. Fig. 3 is a side view showing the discharging device for defective cans. Fig. 4 is a plan view of a 30 part of the same. Fig. 5 is a detached section of part of the discharging device.

Similar letters in each of the drawings indicate like parts.

A is a tank containing water, and B is a rotary carrier, the shaft or axis C of which stands at such an incline that one side of the carrier dips beneath the surface of the water during its rotation, while the opposite side stands above and outside of the water-tank.

E is a vertical chute, into which the cans 40 may be placed after they have been sealed.

F are radial sections, the arms of which extend parallel with each other outwardly from the inner hub of the carrier, these arms 45 being sufficiently separated, so that when they pass beneath the chute E a can will drop into the space between them. The space between each of these can-containing sections is closed, so as to prevent the cans from falling between.

Beneath the carrier is a short section of

track or guide, upon which the cans rest upon their sides in such a position that their ends will stand centrally between the clamps H and I. The outer clamps, H, are in the form of disks 55 which correspond in shape with the outer face of the cans, and these disks are fixed upon the shafts of the gear-wheels J, so that when the gear-wheels J arrive at the curved segmental rack K, which is beneath the surface of the 60 water in the tank, the gears, and with them the disks, will be caused to rotate, and as the cans are clamped between the outer and inner disks they will also be caused to rotate. The inner disks, I, have their shafts loosely 65 journaled in the ends of the radial arms L, which extend outwardly between the can-guides of the carrier, and these arms have rollers M upon their inner ends.

N is a stationary cam fixed around the 70 shaft, about which the carrier rotates, and when the rollers M pass over this cam they and the arms L are forced outward, so that the disks I press against the inner ends of the cans, thus clamping them between the 75 outer and inner disks. These inner disks have elastic rubber plates I' fixed upon them, and these plates serve to stop the vent-holes in the heads of the cans, and also to hold them with an elastic pressure between the 80 inner and outer disks.

It will be seen by this construction that when the carrier is rotated by any suitable mechanism—such as a worm or other gear—or by hand the cans will be carried beneath 85 the surface of the water, and when the teeth of the gear engage with the curved rack the outer disks will be caused to rotate, and as the inner ones turn loosely in the ends of the arms L it will be manifest that the cans will 90 continue to rotate while they are passing beneath the surface of the water. If any leaks occur in the cans, the escaping bubbles of vapor will show which cans are defective. When the cans have been carried by the carrier to the point where they are to be discharged, the inner disks are retracted by reason of the shape of the cam, thus releasing 95 the cans, and they drop upon a spiral inclined chute, O, which is inclosed and heated by any 100 suitable means, as at P, Fig. 1, so as to dry the cans. Those cans which are perfect pass

down the entire circumference of the chute O, and are discharged at the lower end into any suitable receptacle. In order to separate the defective cans from those which are good, I 5 have constructed a supplemental track or chute, Q, Fig. 3, which is placed below the main chute O, and above this supplemental track the floor of the main chute is hinged, so that it may be dropped sufficiently to allow 10 a can to fall through from the main chute upon the supplemental one. This hinged section R is moved by means of knee-levers S, which act upon a connecting-rod, T, and through it the hinged section is depressed, so 15 that when the can reaches this point it will fall through, as before described. The mechanism for effecting this movement is controlled by a lever, U, within reach of the operator, and is employed whenever a defective can passes 20 into the main chute. The section of the main chute is immediately closed after the discharge of the defective can or cans, so that the good ones will be discharged at the lower end, as before described.

25 A lever, U, is connected with each of the can-carriers, and when a can is seen to be defective the lever is turned to stand vertically, as shown in Fig. 3. Its lower end is then in position to pass over and engage the knee-levers S, which are thus depressed, and through 30 the link T the section R will be depressed to a line with the track Q, thus allowing the can to pass over that track. Upon being released the section R rises at once and stands in 35 line with the main track O, over which all the perfect cans travel. This section may be raised by weight or spring, as desired. The levers U are returned to their normal horizontal position as soon as they have passed 40 beyond the tilting section.

Having thus described my invention, what I claim as new, and desire to secure by Letters Patent, is—

1. A can-tester consisting of a water-tank, 45 a rotating carrier mounted at an incline therein, whereby during its rotation one side of the carrier dips beneath the surface of the water, while the opposite side stands above and outside of the water-tank, and means for 50 grasping and holding the cans, comprising clamping-disks and radial sections having separated arms between which the cans lie, substantially as herein described.

2. The combination, with the water-tank, of 55 a rotary carrier mounted on an inclined axis therein, whereby one side is beneath the water and the opposite side outside of and above the water during the rotation of said carrier, clamping-disks at or near the periphery of the carrier, and radial sections having parallel spaced arms which receive the cans, substantially as herein described.

3. The water-tank, the inclined rotary carrier therein, one edge of which dips beneath 60 the surface of the water, the exterior clamping-disks, H, and gears upon shafts which are journaled radially around the periphery of

the carrier, and the segmental rack within the water-tank, with which the gears engage, so as to be rotated thereby, in combination 70 with the inner disks, I, journaled in the ends of the radial arms L, and the central cam, by which these arms and disks are forced outward, so as to clamp the cans between the outer and inner disks, substantially as herein 75 described.

4. The water-tank, the segmental rack therein, the outer disks, and gears by which they are rotated by contact with the segmental rack within the tank, in combination with 80 the inner disks having elastic or rubber faces, the radially-sliding arms L, in the outer ends of which the inner disks are journaled, and the central stationary cam, over which the inner ends of the arms L pass, and by which 85 they are forced outward to clamp the cans while they pass through the tank, and are retracted to release them at the point of discharge, substantially as herein described.

5. The water-tank, the inclined rotary carrier with the clamping-disks, the gears, and segmental rack within the water-tank, by which the gears are rotated, in combination with the table or tracks upon which the cans are delivered and by which they are supported in a desired line until secured between the clamps, substantially as herein described. 90

6. The water-tank, the inclined carrier therein, having one side beneath the water and the other side above and outside of the water, the radial sections having spaced arms for the cans, the vertical chute discharging the cans between said arms, and clamps by which the cans are seized and held, substantially as herein described. 100

7. The water-tank, the rotary inclined carrier, the clamps, mechanism for closing the same upon the cans, and a mechanism whereby the cans are rotated beneath the surface of the water, carried to the point of discharge, 110 and then released from the clamps, in combination with the inclosed discharge-chute and the means whereby said chute may be heated, so as to dry the cans, substantially as herein described. 115

8. The rotary inclined carrier, the water-tank, into which one edge of said carrier dips, the clamps, and mechanism whereby the cans are seized and carried beneath the surface of the water, rotated therein, carried out of the 120 water, and delivered into the discharge-chute, in combination with the supplemental chute situated beneath the first, a movable section in the floor of the upper chute, and a lever and connecting mechanism whereby this section may be opened, so as to discharge any one or more cans into the lower chute, substantially as herein described. 125

In witness whereof I have hereunto set my hand.

W. H. SMYTH.
